UNITED STATES PATENT OFFICE

110,256

DESIGN FOR A DISPLAY BOX

Alfred Neumann, New York, N. Y.

Application May 9, 1938, Serial No. 77,068

Term of patent 3½ years

To all whom it may concern:

Be it known that I, Alfred Neumann, a citizen of the United States of America, residing in city of New York, county of New York, and State of New York, have invented a new, original, and ornamental Design for a Display Box, of which the following is a specification, reference being had to the accompanying drawing, forming part thereof,

Fig. 1 is a perspective view of a display box showing my new design in open position.

Fig. 2 is a rear perspective thereof on a reduced scale.

Fig. 3 is a perspective view, also on a reduced scale, of the display box in closed position.

I claim:

The ornamental design for a display box substantially as shown.

ALFRED NEUMANN.
